United States Patent Office

Des. 212,134

Patented Aug. 27, 1968

212,134

TRAFFIC CONE

Robert E. Dawson, Huntingdon Valley, Pa., assignor to
R. S. Dietz Company, Syracuse, N.Y., a corporation
of New York

Filed Mar. 2, 1967, Ser. No. 6,031

Term of patent 14 years

(Cl. D72—1)

FIGURE 1 is a side elevational view of a traffic cone embodying my new design;

FIGURE 2 is a top plan view thereof;

FIGURE 3 is a bottom plan view thereof; and

FIGURE 4 is a sectional view on the line 4—4 of FIGURE 2.

I claim:

The ornamental design for a traffic cone, as shown.
